CLAIM

The ornamental design for a digital watch, substantially as shown and described.

DESCRIPTION

FIG. 1 is a top perspective view of a digital watch showing my new design;

FIG. 2 is a top plan view thereof;

FIG. 3 is a bottom plan view thereof;

FIG. 4 is a right side elevational view thereof, the left side being a mirror image thereto with the bottom omitted;

FIG. 5 is an end elevational view thereof, the opposite end being a mirror image thereto.
